UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

AUTOMATIC POWER DISCHARGE CHUTE.

Application filed November 15, 1923. Serial No. 675,014.

To all whom it may concern:

Be it known that I, ERICH H. LICHTENBERG, a citizen of the United States, residing at Milwaukee, in the county of Milwaukee and State of Wisconsin, have invented certain new and useful Improvements in Automatic Power Discharge Chutes, of which the following is a specification.

The improvements of this invention have 10 to do with concrete mixing machines, and comprise certain novel means for automatically discharging a concrete mixer at the end of a predetermined period of mixing.

It is known today that there are definite 15 periods of time necessary and desirable for mixing concrete aggregates to obtain what may be styled as a concrete of highest efficiency. To the above end, special controlling machines known as batch-meters are 20 being used today quite commonly, for timing the mixing period of batches of concrete going through a concrete mixer.

My present invention involves a practical 25 construction of instrumentalities operable in conjunction with a batch-meter of a concrete mixer, to set in motion certain power driving mechanism whereby at the end of a predetermined time of mixing, the discharge chute, or means employed for the mixer, 30 will be operated by being shifted to its discharging position. In this way the necessity of an operator of the machine keeping watch on the discharging means to manually actuate the same at the end of the predetermined mixing period is obviated.

With the above in view it may be stated, 40 that the principal mechanical features of my invention consist of a discharge chute for the concrete mixer, power driving means including a clutch device for actuating said chute to turn it over to a discharging position, automatic means operated by the action of the power driving means to render the said clutch means inactive when the discharge chute has reached its discharged 45 position, together with certain manual, or otherwise controlled, parts by which the discharge action of the said chute is prevented before the expiration of the complete mixing period, whereby the discharge chute may be restored to a non-discharging position, and whereby the discharging action

of said chute may be delayed slightly beyond the end of the mixing period, something which may be called for under practical conditions of service. 55

Referring to the illustration of the preferred form of my invention, according to the accompanying drawings.

Figure 1 is a view in elevation looking 60 toward the side of a concrete mixing machine, and showing in detail the automatic mechanism of my invention, the batch-meter feature being illustrated somewhat diagrammatically and the bracket supporting the 65 skip which loads the concrete mixer, being the only portion of the skip shown.

Figure 2 is a view similar to Figure 1 but showing the various parts in their adjustment as when the discharge chute is in its 70 non-discharging position.

Figure 3 is an end view of the mechanism shown in Figure 1, the batch-meter discharge chute and skip features being 75 omitted.

Figure 4 is a top plan view of said mechanism.

Figures 5 and 6 are views of the dog and co-operating hand lever.

Figure 7 is a small diagrammatic view of 80 a typical complete machine having the various cooperating parts, with the action of which my invention is concerned through cooperation involving time relations.

With a view to a full understanding of 85 the present invention, reference is made to the United States Letters Patent of Robb, 1,370,497, issued March 1, 1921, which disclose certain power mechanism for moving a discharge chute of a mixer to its discharging 90 position, the principle of the said invention being followed in the carrying out of my present improvements, the latter however, being applied in a somewhat different 95 way so that the power plant, or engine, of the mixing machine is utilized to drive the chute in moving it to discharging position.

Referring to the parts of the invention 100 in detail, A denotes in fragmentary illustration the drum of a concrete mixing machine, B its discharge chute, and C the pivot bracket which supports the skip D, by which the mixing drum is charged with aggregates to be mixed, E is a batch-meter which may

be of any conventional type, such as set forth in Lichtenberg Patent #1,321,460 of November 11, 1919, or preferably as disclosed by Winkler Patent #1,451,483, issued April 10, 1923. It is notable that as the skip D rises by its pivotal movement with the bracket C supporting it, a rod 1 intermediate the skip and the batch-meter E is actuated and an arm 2 of the batch-meter is moved downwards. The arm 2 is connected with a catch member 3, which leads downwardly and has its nose 3^a adapted to engage a rocker arm 4 pivoted to the rock shaft 5 on which is keyed a rocking dog 6. The dog 6 is normally adapted to engage the projection 7 of a segment 8 mounted on the chute operating shaft 9, carried by any suitable supporting means, not shown, springs 10 being secured at one end as at 11, to the framework 12 of the machine and attached at their other ends to lugs 13 offstanding from said segment 8.

The shaft 9 has an arm, or arms 14, connected by a link, or links 15, with arms 16 on the chute B, so that it will be evident that a pull or pushing movement on the links 15 will cause a rocking of the chute from a non-discharging position extending into the mixer drum A, to a discharging position causing the contents of the drum to flow out, or vice-versa. The arm, or arms 14, are keyed to the shaft 9, and the chute B is supported by a suitable pivot shaft 17. The chute B may be of the type disclosed by Koehring Patent #899,414, issued September 22, 1908, or said chute may be of a different type as desired. The chute actuating shaft 9 will preferably be driven by power means in regard to its movement for shifting the chute to a discharging position.

The driving means for the shaft 9 includes a belt wheel 18, which is keyed to the shaft, a belt or cable 19 passing around said wheel and also around a grooved wheel member 20, which is keyed to a driven shaft 21. The driven shaft 21 is adapted to be operated by any suitable gearing connecting it with the engine of the mixing machine, and said shaft carries a beveled gear 22 meshing with a beveled gear 23. The gear 23 is mounted on a driving shaft 24, being loose on said shaft so that the gears 22 and 23 are normally stationary. A clutch member 25 is keyed to the shaft 24 about opposite the gear 22, and the gear 23 is formed with a clutch flange, or member 26, adapted to cooperate with said clutch member 25.

Suitably engaged with the clutch member 25 is a clutch lever 27 pivoted at its lower end to a bracket 28, and having a loose pivotal and slot connection 29, seen best in Figure 1, with the segment, or loose swinging member 8 carried by the shaft 9.

In effect the springs 10 are attached to the lever 27, through the medium of the

swinging member 8. A restoring lever 30 susceptible of manual operation, is pivotally mounted in a loose manner on the shaft 9, and is adapted to engage with the laterally extending lug 31^a, of a knock out lever 31, which is keyed or otherwise fastened to the shaft 9 to rotate with said shaft. The knock out lever 31 is equipped with an adjustable abutment 31^c consisting merely of an adjustable set screw carried on its free end, said abutment being adapted to engage the upper portion of the swinging segment 8 to move said segment and thereby impart corresponding movement to the lever 27 in a manner to be shortly set forth fully. 80

On the shaft 5, which carries the dog 6 is mounted loosely a hand lever 32. This lever 32 has a locking member 33 adapted by movement of the lever to be engaged with the clutch lever 27 so as to prevent the clutch lever from moving into clutch engaging position. It is notable, that the catch member 3 has a cam 3^b adapted to ride in contact with the shaft 9 to disengage the nose 3^a of the catch member 3 from the rocker arm 4. This action takes place as will now be set forth in a description of the full operation of the machine.

It will be assumed that the knock out arm 31 is in its dotted line position of Figure 1, and the parts substantially as disposed as shown in Figure 2.

The skip D is raised by throwing in the clutch means of the customary mechanism for the purpose, and as the skip goes up the arm 2 is given a downward movement, as previously set forth. Such movement is sufficient to bring the catch member 3 into engagement with the rocker arm 4 at the outer end portion of the latter. The aggregates have been now charged in the mixer, and the batch-meter E is operating so that after the lapse of a predetermined time, usually one minute, the batch-meter operates to indicate the termination of the mixing period, and an upward movement of the arm 2 is caused. Said upward movement of the arm 2 rocks the arm 4, and the dog 6, so as to disengage said dog 6 from the projection 7 on the swinging, or loose member 8. 110

Now this loose member 8, and its connected clutch lever 27 being attached to the springs 10, as soon as the member 8 is released from the dog 6, the springs 10 promptly turn the member 8 on its axis in a contra-clockwise manner, and this shifts the lever 27 to the right, throws into action the clutch members 25 and 26, and causes motion to be transmitted from the driving shaft 24 to the driven shaft 21. The turning of the driven shaft 21 transmits motion through the belt connection 19, to the chute actuating shaft 9, and the shaft 9 begins to turn. 120

It may be noted that when the catch member 3 was pulled upwardly by the arm 2 to 130

disengage the dog 6 from the member 8, the cam 3^b, on the catch member 3, by engaging the shaft 9, causes disengagement of the nose 3^a from the arm 4, releasing the arm and thereby the dog 6, so as to permit the latter to assume its normal position, ready to engage the part 8 at the projection 7.

It will be recalled that in the operation of the parts, the shaft 9 is now rotating under actuation by the wheel 18 and the drive mechanism, said rotation being in a clockwise direction. This operation compels a clockwise movement of the knock out arm 31, which moves from the position 15 of its dotted lines in Figure 1, to the position of its full lines in said figure. When the knock out member 31 has moved approximately 180°, the about 31^c engages the upper portion of the swinging segment 8, and forces said segment downwards at the same time forcing the clutch lever 27 to the left and thereby disengaging the clutch parts 25 and 26. The driving action from the drive shaft 24 to the chute actuating shaft 9, is thus discontinued, and the discontinuance takes place automatically through the operation of the knock out member 31, at the time when the discharge chute B reaches its discharging position, as illustrated in Figure 20

1. Under the present conditions, therefore, the operation of the parts has been such as to automatically shift the chute B from a non-discharging to a discharging position subsequent to the completion of the mixing period controlled by the batch-meter E.

Previous to the action of the knock out lever 31 in disengaging the clutch members 25 and 26, said member moves the segment 8 sufficiently to reset the springs 10; in other words, the springs 10 are again placed under tension, and the dog 6 re-engages with the projection 7 of the member 8 and locks the parts in the tension adjustment. About 45 at the moment the clutch members 25 and 26 are disengaged, the springs 10 restore the parts 6 and 7 to their original cooperation, by a slight upward movement of the part 8, which movement, however, is not transmitted to the clutch lever 27. This is 50 due to the provision between the parts 8 and 27 of the pin and slot connection 27, previously described.

Cooperating with the shaft 9 is a spring actuated mechanism comprising a curved link 35 attached to a spring 36, which is suitably anchored to the frame of the machine by a bolt 37 shown in dotted lines in Figure 1. The link 35 is curved at its upper end so as to extend partly around the shaft 9, said upper end of the link being attached to a wrist pin 38 on the upper belt, or pulley wheel 18. The effective action of the link 35 and the spring 36 is as follows:

When the parts are in the position of Figure 1, the pull of the link 35 through the ac-

tion of the spring 36, tends to act upon the shaft 9 through the wheel 18 to hold the shaft 9 in a position maintaining the discharge chute B in its discharging adjustment. This adjustment is maintained under the positive action of the said parts after the discharge chute has been turned over to its discharging position through the driving mechanism controlled by the clutch devices.

If it is desired now to restore the chute B to its normal position from its discharging position, the manual lever 30 is raised. The effect of such action is to cause said lever 30 to engage the projection 31^a of the knock out lever 31 and raise said arm slightly to turn the shaft 9 contra-clockwise. A slight movement as above set forth, will shift the point of connection of the link 35 and wheel 18 from one side of the axis 9 to the other side, whereupon the spring 36 will come into play to pull downwards on the link 35 and restore the chute B to its non-discharging position, at the same time restoring the arm 31 to its dotted line position of Figure 1, and its full line position of Figure 2. The non-discharging position of the chute B may be a mixing position, or an inactive position entirely.

Should it be desired to delay the clutch engaging movement of the lever 27 after the batch-meter E has operated to cause upward movement of the arm 2, the operator may lift the manual lever 30 so that the locking member 33 thereof, engages in front of the lever 2. This will prevent the lever 27 from moving to the right even though the dog 6 has released the projection 7 and part 8. After the slight delay, such as might be necessary under working conditions, if the operator lowers the lever 32, the springs 10 will go into action and cause the clutch parts to engage automatically and the discharge chute will then turn over to its discharged position.

It is not harmful to delay the action of the discharge chute after the predetermined mixing period has expired, but it would be harmful to advance the operation of the moving of the discharge chute to its discharged position. To prevent any such last mentioned operation, or in other words to prevent throwing over the discharge chute B to its discharging position when the drum is mixing the batch, or before the predetermined mixing period expires, the catch member 3 is formed with outstanding lugs 39 which virtually lock the arm 4 against raising, until the batch-meter arm 2 lifts at the conclusion of the predetermined period of mixing, controlled by the said batch-meter E.

The lever 32 will, therefore, be understood as having a dual function in that it is adapted to actuate the lever 27 to control the clutch

70

operation in the event the batch-meter E is incapacitated or is not a part of the equipment of the machine; and also in the further fact that said member 32 is capable of 5 acting as a lock means when it moves the member 33 into engagement with the lever 27 and permits the engagement to be maintained some little time.

Briefly setting forth the action of the 10 batch meter parts which is substantially the same as found in the Winkler patent previously identified, it is notable that the arm 2 is turned downwards as the member 1 is hit by the skip bracket D, when the latter 15 reaches its uppermost position. The downward movement of the arm 2 is compelled by the link *a* pivoted to the arm *i* which carries the weight *j*. As the arm 2 moves downwards the weight *j* is lifted, and at the 20 same time the dog *b* is brought up by its co-acting spring against the stop *c*. In this way the dog *b* is rocked until it catches in the notch *e* of the member *k* and at this 25 time the link *a* is disengaged from the member *k* through the action of the roller *f* and the nose *g*. As then adjusted the parts are disposed so that the dog *b* holds the member 30 2 against the pull of the spring *h* until the weight *j* comes down and releases the engagement through the tripping of the dog *b* by the knock-out finger *d*. In this manner the spring *h* is permitted to act upon the arm 2 and move the catch member 3 upwards.

It will be evident that the spring 36 and 35 its linkage feature 35 with the connection linking up these parts to the chute, comprise an energy storing device or means, energy being stored in the spring 36 as an incident to the operation of the chute B by 40 the power means constituted by the shaft 24. Furthermore, the catch 3, the arm 4 and the dog 6 with associated parts, form a control means intermediate the batch-meter and the clutch part 25, by which to release 45 the dog 6 and render active the power means through the clutch, to turn over the chute B to discharged position. In effect, furthermore, the springs 10 are energy storing parts for shifting the clutch, and they are 50 placed under tension by the driving action of the power means 24 in a manner which will be evident from the foregoing description.

Having thus described my invention what 55 I claim as new and desire to secure by Letters Patent is,

1. In combination, a discharge chute for concrete mixers, driving mechanism, clutch mechanism intermediate said driving mechanism and the discharge chute for transmitting movement to the chute, catch mechanism for normally maintaining said clutch mechanism inactive, and an automatic means for releasing the catch mechanism 60 and effecting operation of the clutch means

to transmit movement to the discharge chute at a predetermined time.

2. In combination, a discharge chute for concrete mixers, driving mechanism, clutch mechanism intermediate said driving mechanism and the discharge chute, for transmitting movement to the chute, catch mechanism for normally maintaining said clutch mechanism inactive, an automatic means for 70 releasing the catch mechanism and effecting operation of the clutch means to transmit movement to the discharge chute at a predetermined time, and mechanism for automatically discontinuing the operation of the clutch means at a predetermined time. 75

3. In combination, a discharge chute for concrete mixers, driving mechanism clutch, mechanism intermediate said driving mechanism and the discharge chute, for transmitting movement to the chute, catch mechanism for normally maintaining said clutch mechanism inactive, an automatic means for releasing the catch mechanism and effecting operation of the clutch means to transmit movement to the discharge chute at a predetermined time, mechanism for automatically discontinuing the operation of the clutch means at a predetermined time, and a manual means for causing a return movement of the chute after it has been moved by said 95 driving means.

4. In combination, a mixing machine, a chute cooperating with said machine, charging means for the said machine, driving mechanism, clutch means to operatively connect the driving mechanism with the chute to move the latter, control devices normally maintaining the clutch means inactive, and means operated from the charging means for releasing said control devices at a predetermined time. 100

5. In combination, a mixing machine, a chute cooperating with said machine, charging means for the said machine, driving mechanism, clutch means to operatively connect the driving mechanism with the chute to move the latter, control devices normally maintaining the clutch means inactive, means operated from the charging means for releasing said control devices at a predetermined time, and comprising a batch meter initially set by the charging means, and adapted to operate the controlling devices aforesaid at a subsequent predetermined time, to render the clutch means operable 110 so that movement may be transmitted to the chute by the driving mechanism. 115

6. In combination, a mixing machine, a chute cooperating with said machine, charging means for the said machine, driving mechanism, clutch means to operatively connect the driving mechanism with the chute to move the latter, control devices normally maintaining the clutch means inactive, means operated from the charging means 125

for releasing said control devices at a predetermined time, and comprising a batch meter initially set by the charging means, and adapted to operate the controlling devices aforesaid at a subsequent predetermined time, to render the clutch means operable so that movement may be transmitted to the chute by the driving mechanism, and a manually controlled device for delaying the transition of the clutch means to activity beyond the time when the control devices are operated to permit the clutch means to become active.

7. In combination, a mixing machine, a chute cooperating with said machine, charging means for the said machine, driving mechanism, clutch means to operatively connect the driving mechanism with the chute to move the latter, control devices normally maintaining the clutch means inactive, means operated from the charging means for releasing said control devices at a predetermined time, and comprising a batch meter initially set by the charging means, and adapted to operate the controlling devices aforesaid at a subsequent predetermined time, to render the clutch means operable so that movement may be transmitted to the chute by the driving mechanism, a manually controlled device for delaying the transition of the clutch means to activity beyond the time when the control devices are operated to permit the clutch means to become active, said manual means comprising a locking device for maintaining the clutch means out of operation and for effecting actuation of said clutch means.

8. In combination, a mixer, a discharge chute therefor, driving mechanism for turning over said discharge chute to discharging position, clutch means intermediate said driving mechanism and the chute, for connecting the latter to be operated by driving mechanism, control means for the clutch means, normally maintaining the same inactive and preventing operation thereof, and a batch meter for releasing the control means so that the clutch means may operatively connect the driving mechanism with the chute to move the latter.

9. In combination, a batch meter, a mixer discharge chute, driving mechanism, means to connect the driving mechanism to the chute to move the latter, control means including a dog for normally maintaining said connecting means inactive, means operated by the batch meter for locking said dog against release action for a predetermined time, after setting of the batch meter into operation, and including a catch subsequently operable by the batch meter to release the dog and thereby connect the chute to be operated by the driving mechanism.

10. In combination, a batch meter, a mixer discharge chute, driving mechanism,

means to connect the driving mechanism to the chute to move the latter, control means including a dog for normally maintaining said connecting means inactive, means operated by the batch meter for locking said dog against release action for a predetermined time, after setting of the batch meter into operation, and including a catch subsequently operable by the batch meter to release the dog and thereby connect the chute to be operated by the driving mechanism, and means operable by said driving mechanism for transmitting to the chute other movement than transmitted by the driving mechanism, and a manual control device to set the last mentioned means into action for normalizing the chute.

11. In combination, a mixer discharge chute adapted to assume discharging and non-discharging positions, a batch meter, power means to turn said chute over to a discharging position, connecting means between the power means and the chute, including a clutch, control devices controlled by the batch meter and normally maintaining said clutch inactive, and also controlled by the said batch-meter to release the clutch, and thereby cause said clutch to connect the power mechanism with the chute to turn it to discharging position, a power contrivance for restoring the chute to non-discharging position operable by said power means, and manual means to control the action of said power contrivance to at will render it operative to normalize the chute by restoring it to non-discharging position.

12. In combination, a discharge chute for concrete mixers, power means, connecting means intermediate the power means and said chute for turning the chute to discharged position, a power contrivance operable by said power means to store up power by which to normalize the chute so that it assumes a non-discharging position, and means controlling the effective action of said power contrivance.

13. In combination, a discharge chute for concrete mixers, power means, connecting means intermediate the power means and said chute for turning the chute to discharged position, a power contrivance operable by said power means to store up power by which to normalize the chute so that it assumes a non-discharging position, means controlling the effective action of said power contrivance, comprising a manual device for throwing the power contrivance into action and causing it to move the chute back to said non-discharging position.

14. In combination, a discharge chute for concrete mixers, an energy storing device, a linkage connection between said energy storing device and the chute so disposed as to hold the chute in discharging and non-discharging positions power mechanism for op-

- erating the chute and thereby moving said linkage devices to a position storing up energy in the energy storing means, by which to force the chute back to a non-discharging position, and means for releasing said energy storing means for effective action on the chute, substantially as described.
15. In combination, a discharge chute for concrete mixers, a power operating mechanism, clutch means forming part of connections between said power operating mechanism and the chute, means for rendering said clutch means active, whereby the power operating mechanism will move the chute to a discharged position, an energy storing device operated incident to the movement of the discharge chute to discharged position by said power operating mechanism, said energy storage device being so connected with the chute as to restore it to non-discharging position, and means for releasing the energy storing device after the chute reaches a discharging position, whereby the chute is carried back to non-discharging position.
16. In combination, a concrete mixer discharge chute, power means for moving said chute to a discharging position, an energy storing device operated by said power means to store up power by which to move the chute back to non-discharging position, and means for releasing said energy storing device at will subsequent to its operation by the power means.
17. In combination, a concrete mixer discharge chute, power means to move said chute to discharged position, automatic means for disconnecting the power means from the chute when the chute has reached discharged position control devices controll-

ing the application of power by the power means to the chute, and a batch-meter controlling said control means.

18. In combination, a batch-meter, a power operating device, a concrete mixer discharge chute, clutch mechanism to connect the power operating device with the chute to turn the latter to discharged position, a dog normally preventing the operation of said clutch means, a catch operable by the batch-meter for releasing said dog so that the power device will actuate the discharge chute through the operation of the clutch mechanism, and means operated by said power device for rendering the clutch mechanism inactive when the discharge chute reaches a predetermined point in its movement.

19. In combination, a batch-meter, a power operating device, a concrete mixer discharge chute, clutch mechanism to connect the power operating device with the chute to turn the latter to discharged position, a dog normally preventing the operation of said clutch means, a catch operable by the batch-meter for releasing said dog so that the power device will actuate the discharge chute through the operation of the clutch mechanism, means operated by said power device for rendering the clutch mechanism inactive when the discharge chute reaches a predetermined point in its movement, an energy storing device operated by the power means and adapted to carry the discharge chute from discharged position back to non-discharging position, and a manual device for controlling the action of said energy storing device.

In testimony whereof I affix my signature.
ERICH H. LICHTENBERG.
